UNITED STATES PATENT OFFICE.

LOUIS M. WOOD, OF NEW YORK, N. Y., ASSIGNOR TO SPEED-O MULTIPLE VALVE LIFTER CORPORATION, OF NEW YORK, N. Y., A CORPORATION OF NEW YORK.

VALVE-SPRING LIFTER.

Application filed June 20, 1924. Serial No. 721,167.

This invention relates to valve spring lifters, or valve spring lifting mechanism for internal combustion engines, an object of the invention being to provide an improved lifting mechanism wherein a number of valve springs of an engine may be simultaneously elevated or raised under compression and positively held in such position to permit removal of the valves for the purpose of 10 grinding or repair.

A further object of this invention is to provide an improved valve spring lifter comprising a lifting member or bar adapted to operate against a plurality of valve 15 springs, preferably four or more valve springs, and having improved cam means for operating the lifting member or bar whereby the valve springs may be readily elevated under compression with ease and 20 facility.

A further object of the invention is to provide a valve spring lifter wherein the lifting bar or member is operated by a cam supported for operation by a support or 25 post adapted to engage and rest upon the bottom of the valve spring chamber, and so constructed as to be readily and easily located in position and to form a firm and stable support during operation, and also 30 wherein the cam support and lifting bar are guidingly connected in an improved manner so as to guide the lifting bar during operation against displacement.

Other objects of this invention will appear in the following description and appended claims, reference being had to the accompanying drawings forming a part of this specification wherein like reference characters indicate corresponding parts in 40 the several views and wherein Fig. 1 is a front elevation illustrating an embodiment of my invention in operative position with relation to the valve springs of an engine; Fig. 2 is a top plan view of the lifter shown in Fig. 1; Fig. 3 is a rear view illustrating the cam for elevating the lifting member; Fig. 4 is a perspective view illustrating a somewhat modified form of my invention; Fig. 5 is a vertical section through the valve 50 spring chamber showing the lifter in position; Fig. 6 is a front elevation reduced in

size of the lifter shown in Fig. 4; and Fig. 7 is an end view partly in section of the structure shown in Fig. 6.

Before explaining in detail the present 55 improvement and mode of operation thereof, I desire to have it understood that the invention is not limited to the details of construction and arrangement of parts which are illustrated in the accompanying drawings, since the invention is capable of other 60 embodiments, and that the phraseology which I employ is for the purpose of description and not of limitation.

Referring to the construction shown in 65 Figs. 1 to 3 inclusive, it will be seen that the valve spring lifter comprises a lifting member 9 which is adapted to operate against a plurality of valve springs, in this instance being shown as adapted to elevate 70 six valve springs under compression. The lifting member 9 is preferably cast in the form of an angle bar comprising a vertically extending side 10 and a horizontal side 11 extending at right angles thereto. The 75 horizontal portion 11 of the lifting bar is provided with a series of recesses or slots 12 adapted to embrace the valve stems of the engine and provide seats around the edges of the recesses for the valve spring 80 retainers. At opposite sides of the center thereof the horizontal member 11 is provided with a downwardly projecting portion or transverse rib 13, and each rib 13 at the upper face thereof is provided with a 85 transversely extending slot or groove 14. The vertical member 10 of the angle bar is provided with a pair of lengthwise extending slots 15 communicating with the transverse grooves or slots 14, the latter being 90 located substantially centrally of the slots 15. When the lifting member is applied to the engine the companion slots 14 and 15 are adapted to receive studs or bolts 16 which are ordinarily provided for the purpose of securing a cover or door plate in position over the front of the valve spring 95 chamber 17 of the engine.

In the type of engine illustrated in Fig. 1 the enclosing end walls 18 of the chamber 100 17 project inwardly in front of the opposite end valve springs. The present lifter

- is constructed so as to utilize the studs or bolts 16 for the purpose of assisting in positioning and guiding the lifter, and since the horizontal portion 11 of the lifting member must have a length sufficient to extend in front of all of the valve springs, the lifting bar is provided with the horizontal lengthwise extending guide slots 15 so as to enable the lifting bar to be inserted without 5 in the end walls 18 of the chamber without removing the studs or bolts 16. The engine in this instance is provided with a series of six valves provided with valve stems 19 extending into the valve spring chamber 17. 10 The valve springs 20 surround the valve stems and are seated upon the usual cup-shaped retainers 21 which are held in position by means of pins 22 extending through holes in the valve stems. 15 The lifting member is supported for operation by means of a vertically extending post or support 23 and in the present instance, the base 24 of the supporting post or bar is broadened or flared at opposite sides, and 20 provided with an inwardly projecting extension which is bifurcated to provide a pair of supporting feet 25 and 26. A broad base is thus formed for the upright post or bar 23, and in the present instance it will be noted that the feet 25 and 26 are adapted 25 to rest upon the bottom of the valve spring chamber and are spaced apart a distance greater than the distance between a pair of valve springs, thus forming a firm and stable 30 base for the lifting member.

The upper part of the post 23 is formed at opposite sides thereof with vertically extending guide flanges 27 and are located in a vertical guideway 28 formed in an 35 enlarged central part of the member 10. The guideway 28 at the front thereof is provided with inwardly extending guide flanges 29 adapted to overlap the flanges 27. The upright post 23 is bored to receive a 40 rotatable spindle 30 and secured to the inner end of this spindle is a disk 31 which is housed within the guideway 28. Secured to the inner face of the disk 31, as shown particularly in Fig. 3 is a spiral or scroll 45 cam 32, which is adapted to engage a projecting cam lug 33 secured to the vertical member 10 of the lifting bar. It will be understood that by rotating the disk 31 and thereby the cam 32, the cam lug 33 will 50 travel over the outer face or periphery of the cam whereby the lifting member will be elevated or lowered. The cam 32 engages the curved underside of the projection or lug 33, and as shown in Fig. 3 where the 55 lug 33 is positioned above the outer end of the spiral cam, the lifting member will be in its extreme elevated position. By rotating the cam disk 31 counter-clock-wise, see Fig. 3, the lug 33 will travel over the spiral 60 cam and permit the lifting member to be 65

lowered by the pressure of the valve springs and when the lug 33 is located at the inner end 35 of the cam, the lifting member will be in its lowest position. The cam spindle 30 at its outer end is provided with a wrench-receiving portion 36, and by applying the wrench 37 to the part 36 the wrench may be readily manipulated to rotate the cam spindle and the cam. 70

In the foregoing construction it will be 75 noted that the cam lug 33 projects into the guideway 28, and that the inner face of the cam 32 impinges against the inner vertical wall 38 of the guideway, so that by virtue of the vertical wall 38 and the vertical guide 80 flanges 29, the lifting bar 9 will be positively guided in a vertical plane upon the support 23.

Furthermore, it will be noted that the vertical side walls 29 of the guide slot 28 impinge against the opposite ends of the guide flanges 27, these parts thereby cooperating to guide the lifting member in a vertical plane against endwise movement or displacement relatively to the valve springs. From the foregoing, it will be seen that the guiding connections between the support 23 and the lifting member enable the lifting member to be operated in a vertical plane against the valve springs without any substantial 95 tendency to tilt or be otherwise displaced relatively to the valve springs. 100

Referring to the construction shown in Figs. 4 to 7 inclusive, it will be seen that the lifting member 9 is also constructed in the form of an angle bar, having a vertical side 40 and a horizontal side 41, the latter in the present instance being slotted or recessed at 42 for operation against four valve 105 springs in this instance. The recesses or slots 42 are adapted to embrace the valve stems of the engine and provide seats at opposite sides thereof for the valve spring retainers, and these recesses extend the entire width of the horizontal member 41 and terminate in vertical slots 43 formed in the member 40 of the lifting bar. The slots or recesses 43 are advantageous in enabling the operator to insert his fingers therethrough for the purpose of removing the 110 pins 22 after the valve springs have been elevated under compression. 115

In this instance the lifting member is also guided and supported for operation by means of an upright post or bar having an angular base, comprising a vertically extending supporting member or post 45 having an enlarged base 46 which is adapted to rest upon the bottom of the valve spring chamber. 120

The base 46 projects laterally at each side of the post 45 and also has a forwardly projecting portion or foot 47 extending at right angles to the post. The projecting part 47 is recessed at 48 in order to embrace a pro- 125

jecting part of the valve spring chamber and provide clearance. In this construction the post 45 is cylindrical in form and is housed within a boss or projecting guide 5 or sleeve 49 formed centrally at the inner face of the lifting bar 9. It will be noted that the guide 49 projects below the horizontal member 41 of the lifting bar and is tubular so as to entirely embrace the cylindrical guide post 45.

The post 45 is bored transversely intermediate the top and bottom thereof to receive a rotatable tube or tubular spindle 50. This spindle 50 at its inner end (see Fig. 4) is provided with an annular flange 51 which extends over the side edges 52 of a vertical guide slot 53 formed in the guide member 49 of the lifting bar. The tube or spindle 50 projects through a corresponding guide slot 54 formed at the opposite outer side of the vertical member 40 of the lifting bar, and a cam or eccentric 55 is secured to the spindle 50 and is located at the outer face of the vertical member 40 of the lifting bar.

Secured to the extreme outer end of the tube or spindle 50 is a wrench-receiving portion 56. It will be seen therefore that the spindle 50 rotates in the transverse bore of the post 45 and that the cam 55 and wrench-receiving portion 56 are fixed thereto. Also it will be noted that the tubular bore of the spindle 50 is extended through the cam 55 and the wrench-receiving portion 56, thereby permitting the lifter to be inserted over the housing stud or bolt 57 of the engine, this stud or bolt extending through the hollow spindle 50 and through the cam 55 and wrench-receiving portion 56 as shown in Fig. 5.

The lifting bar is provided at the upper central part thereof with a projecting portion 58 which overhangs the peripheral edge of the cam 55 and is engaged thereby for the purpose of elevating the lifting bar on the guide post 45. In the normal position of the parts of the lifting device the tubular guide 49 of the lifting member rests substantially upon the upper face of the base 46 as shown in Fig. 4, and the construction is such that when the lifter is placed in position in the valve spring chamber 59 the horizontal part 41 of the lifting member will be located a substantial distance below the retainers 60 for the valve springs 61, the retainers or seats 60 being supported on the usual removable pins 62 located in the valve stems 63. In this position the edge 64 of the cam 55 will be located in engagement with the underside of the cam projection 58 of the lifting member 40. Upon applying a wrench 65 to the wrench-receiving portion 56 of the cam spindle 50 and partially turning the spindle, the cam 55 will be rotated to bring the cam surface 66 beneath the cam projection 58 and partially lifting the lift-

ing member 40 so as to bring the horizontal portion 41 of the lifting member into engagement with the retainers 60. Thus the initial movement of the cam 55 serves to elevate the lifting bar to a position into engagement with the under sides of the spring retainers and in readiness for the lifting operation of the valve springs. Further rotation of the cam 55 until the straight surface 67 is brought beneath the cam projection 58 will cause the lifting bar to slide upwardly upon the guide post 45 and result in compressing the valve springs 61. The peripheral edge of the cam 55 is provided with a plurality of straight faces shown at 67, 68, 69 and 70, terminating in a stop 71 adapted to engage the cam projection 58 and limit the further rotation of the cam. When the straight face 67 is at rest against the under edge of the part 58 the major portion of the lifting operation of the valve springs will have been accomplished, and further rotation of the cam to bring either of the faces 68, 69, or 70 into position beneath the part 58 is for the purpose of enabling the springs to be raised to slightly different heights. Since the springs vary slightly in different engines it is necessary to elevate the lifting bar to slightly different heights depending upon the particular engine, and this is accomplished by means of the flat cam faces 67 to 70 inclusive which permit slightly increasing variations in the elevation of the lifting bar. It will be further noted that the lifting bar will be locked in elevated position when the several cam faces 67 to 70 inclusive are in engagement with the cam projection 58.

It is important to note that since the tubular guide portion 49 of the lifting bar embraces the post 45, an increased bearing surface of the lifting bar on the guide post is obtained thereby guiding the lifting bar during the operation in an effective manner against any tendency of the lifting bar to tilt or oscillate. Furthermore the lifting bar is readily guided into proper position beneath the valve springs since it is merely necessary to insert the tubular spindle 50 over the stud or bolt 57 which is present in various types of engines for the purpose of clamping the cover plate on the front of the valve spring chamber. The cover plate bolt or stud 57 is thus utilized to position the valve spring lifter properly with respect to the valve springs, but the entire weight of lifting is carried by the guide post 45 having the base 46 thereof resting upon the bottom of the valve spring chamber.

It will also be noted that the present valve lifter is constructed to permit the removal of the valve springs after the valves have been removed and to permit also the ready assembling of the valve springs and retainers while the lifter is in operative po-

sition in the valve spring chamber. The lifting bar, as shown in Fig. 5, is so constructed with relation to the base 46 that the horizontal member 41 will normally be spaced a substantial distance below the retainers 60 when seated on pins 62. After the springs have been elevated to permit the removal of pins 62 and of the valves 63, the cam 55 may be rotated to lower the member 41 to its lowermost position shown in Figs. 4 and 5, thereby causing the valve springs to expand until free from compression and permitting them together with the retainers, to be easily removed, and then placed in position again on the member 41 for elevation under compression.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made or all the modes of its use, I claim:

1. In a valve spring lifter, the combination of a lifting member having guiding means located midway of its length, a single upright post constructed to rest upon the bottom of a valve chamber and projecting thru said guiding means, said lifting member having a plurality of means projecting rearwardly of the post for engaging a plurality of valve springs, and a cam carried by the post adjacent to the front of the lifting member for engaging said lifting member.

2. In a valve spring lifter, the combination of a post, adapted to rest upon the bottom of the valve chamber, a lifting member guided on said post, and means for elevating said lifting member, said post having a horizontal transverse bore for receiving an engine stud or bolt.

3. In a valve spring lifter, the combination of a supporting post adapted to rest upon the engine, a lifting member guided thereon, a rotatable member carried by said post and having a transverse bore to receive an engine stud, and means connected to said rotatable member for elevating said lifting member.

4. In a valve spring lifter, the combination of an upright post constructed to rest upon the bottom of a valve chamber, a lifting member guided by said post midway of the length of said lifting member and having means projecting rearwardly of the post for engaging a plurality of valve springs, and a cam carried by the post at the front side thereof for engaging said lifting member, said cam having a plurality of flat sur-

faces for successively elevating the lifting member into different positions and holding it in each of such positions.

5. In a valve spring lifter, the combination of an upright post constructed to rest upon the bottom of a valve chamber, a lifting member guided by said post midway of the length of said lifting member and having means projecting rearwardly of the post for engaging a plurality of valve springs, and a cam carried by the post at the front side thereof for engaging said lifting member and terminating in a stop for limiting the upward movement of the lifting member.

6. In a valve spring lifter, the combination of an upright post constructed to rest upon the bottom of a valve chamber, a lifting member guided by said post midway of the length of said lifting member and having means projecting rearwardly of the post for engaging a plurality of valve springs, and a cam carried by the post at the front side thereof for engaging said lifting member, said cam having a plurality of flat surfaces for successively elevating the lifting member into different positions and holding it in each of such positions, and terminating in a stop for limiting the upward movement of the lifting member.

7. In a valve spring lifter, the combination of an upright post constructed to rest upon the bottom of a valve chamber, a lifting member having a tubular sleeve encircling and guided by said post midway of the length of said lifting member and having means projecting rearwardly of the post for engaging a plurality of valve springs, and a cam carried by the post at the front side thereof for engaging said lifting member.

8. In a valve spring lifter, an upright post adapted to rest upon the bottom of a valve chamber, a lifting member having a slotted tubular sleeve encircling said post and having means for simultaneously engaging a plurality of valve springs, a rotatable spindle carried by the post and projecting thru the slot of the sleeve, and cam means carried by said spindle for lifting the lifting member.

9. In a valve spring lifter, an upright post adapted to rest upon the bottom of a valve chamber, a lifting member having a slotted tubular sleeve encircling said post and having means for simultaneously engaging a plurality of valve springs, a rotatable spindle carried by the post and projecting thru the slot of the sleeve, and cam means carried by said spindle for lifting the lifting member, said cam means having a plurality of flat surfaces for successively elevating the lifting member into different positions and holding it in each of such positions.

10. In a valve spring lifter, the combination of an upright post constructed to rest upon the bottom of a valve chamber, a lifting member guided by said post midway thereof and of the lifting member for elevating said lifting member, a part carried by the post working in the slot of the guiding means. 50
- 5 of the length of said lifting member and having means at the rear for engaging a plurality of valve springs and having at the front side an overhanging projecting cam engaging portion, and a cam carried by the post at the front side thereof for engaging said overhanging portion for elevating the lifting member.
10. In a valve spring lifter, the combination of an upright post constructed to rest upon the bottom of a valve chamber, a lifting member guided by said post midway of the length of said lifting member and having means at the rear for engaging a plurality of valve springs and having at the 55 front side at the top thereof an overhanging projecting cam engaging portion, and a rotatable stepped formed cam carried by the post at the front side thereof for engaging said overhanging portion for elevating the lifting member. 60
15. In a valve spring lifter, the combination of a lifting member having midway of its length guiding means, a single upright post projecting through said guiding means and having an angularly extending foot adapted to rest upon the bottom of a valve spring chamber, said lifting member having a plurality of means for engaging a plurality of valve springs, and a cam pivotally connected to said post for elevating said lifting member. 65
20. In a valve spring lifter, the combination of a lifting member having midway of its length a projecting slotted guiding means, a single upright post projecting thru said guiding means and having an angularly extending foot adapted to rest upon the bottom of a valve spring chamber, said lifting member having means for engaging a plurality of valve sprigs, and a rotatable cam pivotally connected to the post transversely 70
25. In a valve spring lifter, the combination of a lifting member, a cylindrical post adapted to rest upon the bottom of the valve spring chamber and extending vertically through said lifting member and a cam pivotally supported by said post for elevating said lifting member. 75
30. In a valve spring lifter, the combination of a lifting member having a laterally projecting guide portion, a post extending vertically therethrough, and cam means pivotally carried by said post for elevating said lifting member. 80
35. In a valve spring lifter the combination of an upright support adapted to rest on the engine and having a transverse bore, a lifting member guided on said support, said support having a transverse tubular extension provided with a bore alined with said transverse bore and also provided with a wrench portion, and a cam carried by said extension for elevating the lifting member. 85
40. In a valve spring lifting mechanism, the combination of a lifting member comprising a vertical portion and a horizontal portion, a post extending vertically through said horizontal portion, guide means carried by the vertical portion and cooperating with said post, and a cam supported by said post for elevating said lifting member. 90

Signed at New York city, N. Y., this 28th day of April 1924.

LOUIS M. WOOD.
